UNITED STATES PATENT OFFICE.

HENRY A. WISE WOOD, OF NEW YORK, N. Y., ASSIGNOR, BY MESNE ASSIGNMENTS, TO
WOOD NEWSPAPER MACHINERY CORPORATION, OF NEW YORK, N. Y., A CORPORA-
TION OF VIRGINIA.

MACHINE FOR MAKING STEREOTYPE PRINTING-PLATES.

1,164,607.

Specification of Letters Patent. Patented Dec. 14, 1915.

Application filed January 12, 1910. Serial No. 537,700.

To all whom it may concern:

Be it known that I, HENRY A. WISE Wood, a citizen of the United States, residing at New York, in the county of New York and State of New York, have invented a new and useful Machine for Making Stereotype Printing-Plates, of which the following is a specification.

This invention relates to a machine for casting stereotype printing plates. While some of the features thereof are capable of use generally for that class of machines, yet the invention is illustrated in a form in which it is particularly applicable to the casting of flat plates.

Among the objects of the invention are to provide a new machine adapted automatically to take one matrix at a time from a pile of matrices in a magazine, deliver it in the mold, fill and cool the mold, discharge the cast plate, trim, shave and deliver it; and deliver the matrix when desired; to provide a new matrix feed adapted to be adjusted so that the matrices can be fed in such a way that any desired number of plates can be cast from each matrix, or a plurality of plates from any matrix or matrices and a different number from the others, or a continuous series of plates from a single matrix; to provide a magazine capable of accommodating matrices of different sizes; to provide for delivering the matrices by means of a following matrix or dummy matrix pushing each matrix out of the mold; to provide a melting pot having a recess to contain the pump so as to overcome the pull due to contraction of the body of the metal in the pot due to cooling; to provide means for operating the pump valve so that it shall be automatically closed by the first part of the upward movement of the pump plunger unless it is held open by means controlled by the matrix or dummy matrix; to provide means whereby if one or more of the matrices or dummy matrices have their corners cut away under the pump valve trip device, the pump valve will remain open and no plates will be cast; to provide a mold adapted to be resiliently held against the pump nozzle to allow of expansion and contraction of the parts so as to keep the mold and pump nozzle in proper relation to each other thereby preventing leakage of metal; to provide for water cool-

ing the casting box by means of a spray; to provide an upper casting box adjustable for different thicknesses of plates; to provide side gages for the casting box of an improved form so constructed as to form the bevels of the side of the plate, attached to the upper half of the casting box, and variable in size to suit plates of different sizes, and adapted to act as guides for the plates when they are being removed from the box; to provide a rear side gage adjustable in position to suit various sizes of plates; to provide end gages attached to the lower half of the casting box and acting as guides for the matrix, the gage at the head end of the plate adjustable for different sized plates, and having means for forming the groove for the first carrier hooks; to provide a first carrier having an adjustable stroke for plates of different sizes and having hooks adjustable sidewise to accommodate said plates; to provide an improved shaving knife having a preceding spring-pressed roll to prevent buckling of the plate and hold the plate in position; to provide means in connection with the casting box whereby the bevels on the side of the plate and the thickness of the plate shall be sufficiently true for some classes of work to avoid the necessity of the first saws and shaving mechanism; to provide convenient and practicable means for trimming two edges of each plate and then the other edges; and also to provide an improved arrangement of the first saws and shaving mechanism for certain classes of work.

The invention also involves improvements in various details of construction as will appear hereinafter.

Reference is to be had to the accompanying drawings in which—

Figure 1 is a plan of a flat stereotype plate casting and finishing machine constructed in accordance with this invention with some parts removed so that interior construction can be seen. Fig. 2 is a side elevation of the same with parts removed. Fig. 3 is an end elevation of the same. Fig. 4 is a sectional view on the line 4—4 of Fig. 1. Fig. 5 is a side elevation of a portion of the machine showing the magazine for holding the matrices in position to be fed into the mold. Fig. 6 is a plan of the same. Fig. 7 is an end elevation of the parts shown in

Fig. 5 with parts in section. Fig. 8 is a similar elevation with parts removed to show interior construction. Fig. 9 is a plan similar to Fig. 6 with parts removed and 5 with a matrix in position. Fig. 10 is a sectional view on the line 10—10 of Fig. 9. Fig. 11 is a sectional view like Fig. 10 showing the parts in a different position. Fig. 12 is an elevation of a portion of the matrix magazine. Fig. 13 is a plan of a matrix suitable for use in this machine. Fig. 14 is a sectional view on the line 14—14 of Fig. 1. Fig. 14^a is a section of a detail. Fig. 15 is an end view of the mold, partly in section. Fig. 16 is an elevation of a portion of the mold showing the cooling means. Fig. 17 is a central view on the line 17—17 of Fig. 16 in the direction of the arrow. Fig. 18 is a plan of the parts of the mold below the line 18—18 of Fig. 19. Fig. 19 is a sectional view on the line 19—19 of Fig. 18. Fig. 20 is an elevation looking along the arrow 20 of Fig. 18, looking in the opposite direction. Fig. 21 is an elevation looking 25 along the arrow of Fig. 18. Fig. 22 is a sectional view on the line 22—22 of Fig. 18. Fig. 23 is an elevation of parts shown in Fig. 18. Fig. 24 is a longitudinal sectional view of the melting pot and casting pump 30 showing other features in elevation. Fig. 25 is an elevation of the casting mouth thereof. Fig. 26 is a vertical sectional view of part of the mold showing the plate in position to be removed. Fig. 27 is a similar 35 view showing the plate partially trimmed on the edge. Fig. 28 is a plan of a portion of the device at the rear of the portion shown in Fig. 1. Fig. 29 is a sectional view on the line 29—29 of Fig. 28. Fig. 30 is a sectional view on the line 30—30 of Figs. 1 and 28, a part being shown in section on the line X—X in Fig. 1. Fig. 31 is a transverse sectional view on an enlarged scale of a portion of a guide shown in Fig. 30. Fig. 32 is a 40 sectional view on the line 32—32 of Fig. 28. Fig. 33 is an elevation of the plate delivery means shown in Fig. 4, and Fig. 34 is a sectional view of a detail.

This invention is shown in a form for 50 casting stereotype plates and as embodying a frame 30 having means for supporting various parts of the machine. At one end of the frame are brackets 31 supporting the transverse driving shaft 32 which is provided with a driving pulley 33 (Figs. 3, 4 and 28.) By bevel gears 34 this shaft drives a short longitudinal shaft 35 having a worm 36 for driving a worm wheel 37 fast on a transverse shaft 38 (Figs. 1, 2 and 4) which 55 by bevel gears 39 drives a longitudinal shaft 40 at the front side of the machine. At one side of this frame are a pair of laterally projecting brackets 41 separated from each other and on which is supported the magazine for the matrices. This magazine is

shown particularly in Figs. 1 and 5 to 12 as comprising vertical side members 42 and 43 resting on the brackets 41. Both of these side members are provided with flanges 44 and 45 which extend along the supporting 70 brackets 41. These flanges project inwardly a short distance and serve to guide the corners of the matrices. On the delivery side of the magazine the side members are adjustably held together by means of cross 75 bars 46. One of the side members is firmly secured to its bracket and the other is adjustable thereon. Both of the side members are provided with two slots in which the ends of these cross bars 46 extend and the latter are screwed or otherwise fixed to these side members in the slots and are provided with fastening pieces 47. Each of the cross bars 46 is provided with a longitudinal slot 48 through which pass screws or bolts 49 by 80 which it is secured adjustably to the other side member. In this way, the distance apart of the side members, and therefore, the width and length of the magazine, can be regulated as desired so as to provide for 85 matrices M of any desired width and length.

Extending along the side of the magazine are a pair of reciprocable rods 50. On each of these rods are mounted two fingers 51 which project toward each other through 90 horizontal slots 52 in the side members of the magazine and are provided at their inner ends with supports 53 in the magazine on which the matrices are supported, as indicated more particularly in Fig. 10. The 95 matrices are dropped by the longitudinal motion of these supports 53 which permits a single matrix to be dropped at a time on a central and two side supports 54. Adjustably mounted on the cross bars are retaining 100 bars 55—55 extending inwardly and spaced from the bottom of the magazine a distance sufficient to permit the matrices to be discharged under them.

The rods 50 are guided in boxes 56 supported by the flanges 44 and 45 and by boxes 57 supported at the other ends of the side members 42 and 43. On each of the rods 50 is a key 58 on which the fingers are adjustable longitudinally. They are held in position by screws 59. The dropping of the matrices one by one is accomplished as follows:—Each matrix is provided with a pair of opposite edge notches M' near one end, and with a pair of similar opposite edge 110 notches M² at a greater distance from the other end. These notches are all of a shape and size to permit the supports 53 to pass through them, and are the same distance apart as said supports. The matrices are 115 placed in the magazine alternately, that is, so that notches M' and M² are alternately at the head or feeding edge of matrix. When the rods 50 move forward, if the supports register with the notches, the bottom 120

matrix will drop and the next matrix will rest on the supports (Fig. 11.) Then on the completion of the reverse motion the second matrix will drop.

In order to move the rods 50 the shaft 40 is provided with a gear or pinion 61 which operates a gear 62 on which is mounted a double throw cam 64. Gear 62 rotates on a stud 63. This cam operates a spring-pressed cam roller 65 on a lever 72 which is connected by screw 73 to lever 66 which is provided with a gear segment 67. This gear segment meshes with a pinion 68 and turns the same periodically so as to oscillate a pinion 70 and shaft 69, and reciprocate the pair of rods 50 which are provided with racks on the bottom. This carries the fingers 51 back and forth periodically and uniformly so as to deliver the matrices under them, as has been described. To adjust the throw of the lever 66 to accommodate the location of the notches M' and M^2 a rod 66^a is pivoted to the lever and has an adjustable collar 66^b which engages the bracket on which the rod is mounted. The lever 66, and therefore the roller 65, is yieldingly held in position by a spring 66^c. The screw 73 can be removed so as to leave the lever 66 free so that no matrices will be fed. Then if the screw 73 is out the lever can be turned to feed a matrix and held for casting any number of plates from it. On the shaft 69 is a handle 71 by which the shaft can be turned independently of the power, and held so as to cast any desired number of plates from a single matrix.

On the shaft 40 is located a cam 75 which operates a spring-pressed forked lever 76. By means of a lever 77 this reciprocates a slide 78 which is mounted on a guide or support 79. This slide carries a pair of ears 80 supporting a rod 81 on which are mounted two arms 82 each having a pushing finger 83 at the end thereof. One of these is adjustable along the rod to provide for matrices of different widths. Every time the roll 65 comes either on the low or high part of the cam 64 the slide 78 is moved to discharge a matrix from the magazine. If it is desired to deliver matrices at alternate rotations of the shaft 40, so as to cast two plates from each matrix the cam 64 is changed. In this case the cam would have one high and one low part of approximately equal length. This slide 78 then moves forwardly and the fingers 83 which come up between the brackets 41 engage the rear of the matrix deposited thereon to push it out of the magazine, as shown more particularly in Fig. 8.

The side member 42 is shown as stationary, and the side-member 43 is shown as provided with a projection 85 having slots 86 through which it is adjustably secured by screws 87 to one of the brackets 41. A

reciprocating supporting plate 91 is mounted to move in vertical guides 92 on the frame, and carries the lower casting box 93.

The upper casting box 95 is supported on two brackets 320 on which are standards 79 321 carrying rods 322 and 332 (see Figs. 1, 2 and 24). The upper box is supported from the rods by plates 323. On the rods are springs 324 bearing on the plates 323 nearest the melting pot, and on collars 325 fixed 75 to the rods. These springs obviously tend to keep the upper box yieldingly against the nozzle. The lower box 93 is held up against the nozzle by a spring 326 operating a rock shaft 327 which is provided with an arm 80 328 engaging the end of the box. This allows for expansion and contraction and keeps the boxes in proper relation to the pump nozzle so as to prevent leakage.

Through the bases of the plates 323 pass 85 thimbles 329 which extend slightly below the bottom thereof. A bolt 330 extends through each thimble and these bolts fasten the upper box to the standard 321. The thimbles rest on the distance piece by which the elevation 90 of the upper box is controlled. This construction permits the springs 324 to keep the upper box up against the nozzle. The rod 332 rests in open slots on the brackets 321.

The two casting boxes 93 and 95 are provided with cooling water inlet and outlet pipes 96. See Figs. 16 and 17. Inside each of these boxes is a chamber 97 for receiving water from the pipes each having a perforated plate 98 through which the water is 100 discharged in a spray on the inner surfaces of the bottom and top plates of the casting boxes. Between these bottom and top plates is the mold proper. It has side gages 99 and 100 respectively which form the bevels of 105 the sides of the plates. See Figs. 18 to 23. These gages are fastened to the upper casting box 95 and one of them can be adjusted out and in to provide for casting plates of different sizes. When the plate is removed 110 from the casting box, as will be explained hereinafter, the upper inner beveled edges 101 of these gages act as guides for the sides of the plates. Their adjustment is secured by means of screw connections 102 115 or in any other desired way. The casting box is also provided with end gages 103 and 104 one of which is adjustably fastened to the lower casting box section 93. These act as guides for the matrix when it is being 120 introduced into the casting box. The one at the head end of the plate is adjustable in the same way as the side gages or in any other desired way, for plates of different sizes and it has a longitudinal projection 105 125 which forms a transverse groove P^3 in the cast plate for the first carrier hooks. The matrices are discharged from the magazine under the end gages 103 and 104 of the casting box and positively moved into register 130

with the side gages by means of the pusher fingers 83. The gage 103 projects down at the side and rests in a dovetailed groove 103^a on the casting box. It is fastened to the 5 box at one end and free at the other so as to allow of free contraction and expansion. Likewise the gage 104 is fixed at one end to a fixed adjustable knee 104^a and is free at the other, where it is dovetailed to a companion knee 104^b as shown in Fig. 20. Then 10 the supporting plate 91 is raised by a cam 106 on the shaft 40 which operates an arm 107 on the frame 30 and provided with a connecting rod 108 extending back toward the center of the machine. With this latter rod 15 is pivotally connected an arm 109 on a rock shaft 110 which is provided with another arm 111, these parts constituting in effect a bell-crank. The arm 111 is pivotally connected with a connecting rod 112 which is 20 pivoted to the bottom of the plate 91 (see Fig. 14). On the frame is mounted a bracket 113 provided with an adjustable stop 114 for limiting the motion of the connection 25 between the parts 111 and 112 and preventing them from going too far beyond the center.

Mounted in a vertical guide 125 on the upper section of the casting box is a pin 126 30 which projects down through into the casting box so that as the lower section of the box moves up, if the matrix is in position, the matrix will engage the bottom of the pin and raise it enough to move an arm 127 35 which is mounted on a rock shaft 128. If, however, the corner of the matrix or dummy matrix is cut away, the parts can be moved up into casting position without moving the pin so that this shaft will not be operated. 40 When this shaft is turned by the proper closing of the box containing a complete matrix and adapted to receive metal, this causes a latch 129 thereon to be moved from the path of the top of a vertical rod 130 having a 45 valve 131 thereon; but if the parts operate with a dummy matrix in position which has the rear left-hand corner cut away, the latch 129 will remain over the top of the rod 130 and hold the latter down. The object of this 50 construction will be seen from the following description of the operation of the pump.

On the shaft 40 is a cam 140 operating a roller 141 on a spring pressed arm 142 which is fixed on a rock shaft 143. This rock 55 shaft operates an arm 144 which reciprocates a pump plunger 145 in a melting pot 146. This plunger is mounted in an open-bottomed cylinder 147 submerged in the pot and the cylinder is located in a recess 60 within a perforated wall 148 in the pot to protect the pump against the tension or pull due to the contraction of the body of metal in the pot upon cooling. Now each rotation of the cam 140 will move the plunger 65 through a complete reciprocation in the

pump cylinder. The upward reciprocation of the plunger will force metal upwardly through the nozzle 149 into the mold unless the valve 131 is held down by the latch 129 as above explained. Then the reciprocation of the plunger will only cause a circulation of the metal in the pump up through the passage 150 which the valve 131 controls. It will be seen, therefore, that the pump valve 131 is closed by the first part of the 70 upward movement of the pump plunger on account of the tendency of the metal raised thereby to flow out of the opening 150 unless the valve is held down by the latch, so that if one or more of the matrices or dummy matrices in the mold have their corners cut away all the parts of the pump will 75 operate but the metal will not be forced into the casting box.

If it is desired to keep the valve 131 down 80 all the time so that no metal can be forced from the pump, as for instance while repairing machinery, the rock shaft 128 is turned to bring a catch 152 over a fixed collar 153 on the rod 130. This can be done by pulling 85 up on the arm 127 when in the position shown in Figs. 2 and 15. The parts will 90 remain in this position and the machine can be operated without danger of flooding the parts with metal.

The nozzle of the pump is provided with a slot 155 of a width in proper proportion to the width of the mold cavity in the casting box. The height of the slot is regulated by the position of a top part 156 held in adjustable position by bolts 157 passed through elongated orifices therein. Both the top and bottom members of the end of the nozzle are shown as cooled by air passing through 95 passages 158. This is provided to cause the 100 metal to chill at the proper place between the plate and the body of metal left in the 105 nozzle.

When the casting boxes close another 110 plate will be cast from the same matrix unless another one or a dummy is fed into the lower casting box while in lowest position. In that case the old matrix will be forced 115 out of the box by the rear matrix guided by the end gages and drop at the rear of the frame.

As has been stated, the casting box is so constructed that the projection 105 on the gage 104 forms a notch P^a in the forward end of the plate P and on the under side 120 thereof. This notch is made use of in withdrawing the plate from the casting box. On the shaft 38 is a cam 165 which operates a roller 166 on a lever 167. This lever is held up so that the roller engages the cam surface by a spring 168. On the end this lever is provided with a gear segment 169 meshing with a pinion 170 on a transverse shaft 171 so that this shaft will be caused to oscillate. On this shaft is a gear or pinion 172 130

which operates a sliding rack 173. On this sliding rack is a cross bar 174 to which are adjustably fixed a pair of arms 175 that extend forward. See Figs. 26 and 27. Each 5 of the arms is provided with a pivot pin 176 on which is pivotally mounted a finger 177 having a hook 178 thereon adapted to engage in the notch P³, as indicated more particularly in Figs. 26 and 27. A spring 179 10 holds the hook yieldingly in position for engaging the plate while held by the side gages on the upper part of the box so that upon the reverse motion of the sliding rack, the plate will be drawn out of the box longitudinally. The plate is drawn on a pair 15 of supports 180 each of which is bifurcated to permit the hook to pass between them. These supports are laterally adjustable along a cross rod 289. The stroke of the lever 167 is adjustable for plates of different sizes. This is done by providing a collar 181 on the spring rod. This collar has a set screw which comes up against a bracket 182 on the frame and according to its adjustment holds the cam roll off the low part of the cam, so as to shorten the stroke. It will be observed also that as the hooks draw the plates out in the manner just described, they are brought against the edge trimming 20 saws 183 and their edges by which they are held up in the upper half of the mold are trimmed while being drawn out. These saws are operated by a pulley 184 (Fig. 3) on the transverse shaft 32 at the end of the 25 machine. This pulley has a belt 185 upon which it passes around idlers 186 to the pulley 187 on the saw shaft. For some classes of work these saws can be dispensed with as the edge bevels can be made accurately enough by the gages.

Between the supports 180 is an adjustable support 188 which helps carry the plate when it has been moved out by the first carrier hooks 178. When the plate reaches the position on the supports 180 and 188 its course is changed exactly at right-angles and the plate is delivered from the main body of the machine by the following mechanism. On the shaft 40 are a pair of cams 190 and 190^a operating rollers 191 and 191^a on a pivot arm 192 which carries a gear segment 193. This gear segment operates a pinion 194 which oscillates a shaft 195 mounted in brackets 196 on the frame and this shaft through a gear or pinion 197 reciprocates a rack 198. This rack is fixed to a slide 189 which moves along a transverse guide 199. Upon the slide is located a rod 200 having fixed pushers 201 which engage the rear of the plate and slide it along over a guide 202. This brings the plate into a position on a flat support 203 secured on a fixed bracket 204 on the side of the frame. This support is provided with an upturned edge 205 against which the edge of the plate

is adapted to be moved. It is provided also with a block 305 entering in the notch P³ in the plate to prevent the blade moving the plate back on its rearward travel.

Mounted on the end of the shaft 38 is a 70 crank arm 206 having a roller 207 thereon adapted to move in a vertical groove 208 on a slide 209. See Figs. 28 to 31. This slide moves in ways 210 on the bracket 204. Carried on this slide is a blade holder 211 on 75 which is mounted a shaving blade 212. Also on the slide are arms 213 carrying a roller 214 yieldingly pressed down by springs 215. As the slide travels longitudinally of the machine it passes the blade over the plate 80 and shaves the back thereof the roller pressing down on the plate in front of the blade to prevent buckling of the plate. It will be understood that the edge of the plate is held against the projection 205 at this time. 85 For some classes of work the shaving blade can be dispensed with as the plate can be cast to thickness with a few degrees of accuracy. After this shaving operation takes place, the rack 198 is moved back to get another plate. When the slide 189 moves back there is no plate in position behind these pushers 201 and there is no obstacle to their backward motion. On the slide are two rock shafts 217 having pushers 218 and 219 90 respectively fixed thereon. Each rod has an arm 220 extending upwardly between a pair of lugs 221 on a rod 222. This rod is carried in bearings fixed on the slide and moves with it but is free to slide in its bearings. As the slide approaches the end of its stroke as shown in Fig. 30, the rod 222 comes against adjustable stop 223 on an arm 224. The continued motion of the slide moves the rod back so as to tip the pushers 100 105 218 and 219 up out of the way of the plates, so that the slide can move back. As it approaches the other end of its travel the rod is moved the other way by the adjustable stop 225 on another arm 225^a. This turns 110 the pushers back into position with their lower ends below the tops of the plates so that the pushers 218 are ready to remove a plate from the support 203 and the pushers 219 to advance the preceding plate out of 115 the machine.

As each plate is pushed off the support 203 its edges engage guides 226 and 227 of the same shape as the end gages of the mold so as to fit the edges of the plate, and it moves on laterally adjustable supports 230 and passes over a pair of saws 231 which cut off the head and tail and trim or bevel the edges. These saws are operated as follows:—The shaft 32 by means of beveled gears 233, drives a longitudinal shaft 234 on which is a pulley 235 which by means of a belt 236 drives the saw pulley 237. This belt passes over adjustable idlers 238. At the sides of the supports 230 are edge sup- 125 130

ports 240 having upwardly projecting guides for engaging the beveled edges cut by the saws 231 and guiding the plate during the rest of its course. The plate is held under edge plates 241 and 242, one of which is laterally adjustable.

On the shaft 40 is a worm gear 245 driving a transverse shaft 246, on which are two gears or pinions 247 and 248 at the rear of the machine. The gear 247 drives gears 249, 250 and 251, arranged in alinement. The delivery boxes 255 are provided with rack teeth 256 on their sides, which are engaged by the gears 248 and a gear 258 on the shaft 259 on which is the gear 251. These boxes slide down in ways 260 until they hang below the machine and can be removed by hand. They have pins 261 and hooks 262 so that they can be inserted as is indicated by the arrows in Fig. 30. They are dropped the distance of one shelf at each operation of the machine.

The connections between the shaft 38 and gear 37 comprise a disk 261 fixed on the shaft 38 and having a pin 262 passing through it into the web of the gear 37. This pin is provided with a reduced cross section so that in case of any obstruction to the proper operation of the machine sufficient to cause breakage, the breakage will occur at this point. The same construction is provided between the beveled gear 39 and a disk 263 on the shaft 40. The same construction is shown in connection with an arm 264 keyed on the shaft 143 and connected with the lever 144 at a distance from the point at which the latter is freely pivoted on the shaft. In this case the breaking point is located between the end of the arm 264 and a boss 265 on the lever 144.

In operation the matrices are placed in the magazine with the notches M^1 and M^2 arranged alternately so that as the feeding rods move back and forth, one matrix will be fed down at the end of the forward stroke and the next one at the end of the reverse stroke. When it is desired to operate the machine one or a definite number of times without casting a plate, one or more dummy matrices with their corners cut away are placed in the magazine. Under ordinary conditions a matrix will be fed into the mold under the end gages which hold its edges on the lower casting box. Then the latter rises, lifts the top section a very slight distance and brings the parts into registration with the nozzle ready for the casting of a plate. At this time the spring has brought the rock shaft 143 around into such position as to raise the plunger in the pot, which closes the valve and thus forces the metal into the casting box, with a yielding pressure. The spring continues to exert a pressure on the plunger while the metal is cooling in the mold to compensate for the contraction of

the metal. The cams have sufficient dwell at this point to allow the casting box to remain closed long enough to allow the plate to harden. Then the lower box moves down. The upper box remains substantially in the first position with the cast plate held by the side gages which underlie its edges, as has been stated. As the lower box moves down the first carrier hooks move up into the position shown in dotted and then in full lines in Fig. 26 where they enter the notches P^3 in the plate. Then they start to move as shown in Fig. 27 and draw the plate on the supports 180. During this operation the projecting beveled edges formed by the side gages are guided by the latter and are then trimmed by the saws. When the plate reaches the end of its travel on the supports 180 the pushers 201 are at the end of their stroke and ready to move back to push the plate laterally from this position on the support 203. These pushers then move back and dwell at the rear of the stroke during the entire reciprocation of the hooks.

The next operation of the plate is to shave the back by means of the shaving blade 212, the operation of which has been described in full. During the time when the pushers remain in their rearward position the shaving blade moves back. On the next operation while the pushers 201 start forward to move the next plate into position on the support, the pivoted pushers 218 engage the plate which has just been shaved and push it out on the supports 230, as has been described, at this time the other edges being trimmed by the saws 231.

It will be observed that as there is a plate on the support 203 during the rearward motion, the second set of pushers are lifted by the operation of the sliding rod as has been previously described. But the first set of pushers does not have to be lifted because when they travel back there is no plate in their path. During each forward motion the third set of pushers 219 deliver the plates from the position in which their ends are trimmed, into the delivery boxes.

It will be seen therefore that one plate can be cast from each matrix, or any desired number, or a plurality of plates can be cast from the first or any particular matrix and a different number from the rest of them, or a continuous series of plates can be cast from a single matrix. It will be seen also that the used matrices are pushed by a succeeding matrix or dummy from the casting box and that the dummy matrices will be delivered in the same way. The way in which the pump is prevented from operating is exceedingly simple and effective and of course results in allowing the other operations of the machine to take place without casting a plate, as for example, at the end of any continuous casting operation a dummy would be introduced

so as to permit the last matrix to be delivered. The various mechanisms are adjustable in all necessary ways to take care of plates of different sizes.

6 While I have illustrated and described a preferred embodiment of the invention and shown it as applied to the casting of flat printing plates, I am aware that many modifications can be made in the various details 10 of construction and the sequence of operations and that most of the parts can be employed for casting stereotype plates, and in fact other articles, of different shape and character from the plates specified and that 15 certain parts can be omitted without departing from the scope of this invention. For example, the first or second sets of trimming saws, or both, can be omitted, and even the shaving device can be omitted (the corresponding functions being dispensed with) 20 without reorganizing the remainder of the machine. Therefore, I do not wish to limit myself to the details of construction or sequence of operations or shape of plates de- 25 scribed herein but

What I do claim is:—

1. The combination in a mechanism for making stereotype printing plates, of a casting device, and means for feeding a matrix thereto.

2. The combination in a mechanism for making stereotype printing plates, of a casting device, and means for feeding a matrix thereto and ejecting the same therefrom.

3. The combination in a mechanism for making stereotype printing plates, of a casting device, and means for feeding a matrix thereto and ejecting the same therefrom after a number of plates have been cast.

4. The combination in a mechanism for making stereotype printing plates, of a casting device, a matrix supplying device, and means for feeding the matrices successively to the casting device.

5. In a machine of the character described, the combination of a magazine for holding stereotype plate matrices, means for automatically feeding said matrices out of the magazine, and means for rendering the feeding means inoperative.

6. In a stereotype printing plate making machine, the combination of a magazine adapted to hold matrices, and means for feeding matrices therefrom.

7. In a machine of the character described, the combination of a magazine for holding stereotype plate matrices, means for automatically feeding said matrices out of the magazine, and hand operated means for rendering the feeding means inoperative, and for feeding the matrices from the magazine at will.

8. In a machine of the character described, the combination of a magazine for holding stereotype plate matrices, means for

feeding said matrices out of the magazine in regular order, and manually controlled means for feeding the matrices at will.

9. In a machine of the character described, the combination of a magazine for holding stereotype plate matrices, means for feeding said matrices out of the magazine in regular order, manually controlled means for feeding the matrices at will, and a casting box for receiving the matrices from the magazine.

10. In a machine of the character described, the combination of a magazine for holding stereotype plate matrices, means for automatically feeding said matrices out of the magazine, means for rendering the feeding means inoperative and a casting box for receiving the matrices from the magazine.

11. In a stereotype plate casting machine, the combination of a matrix magazine adapted to hold a plurality of matrices, means for discharging matrices therefrom, and a casting box in position to receive a matrix as it is discharged from said magazine.

12. In a stereotype plate casting machine, the combination of a magazine for holding matrices, a casting box and means for automatically discharging a matrix from the magazine into the casting box.

13. In a stereotype plate casting machine, the combination of a matrix magazine, means for discharging matrices horizontally therefrom, and a casting box having means for receiving a matrix as it is discharged from the magazine.

14. In a device of the character described, the combination of a matrix magazine, means for delivering matrices therefrom, a casting box, and gages on the casting box in position to receive the edges of said matrices as they are delivered from the magazine.

15. In a machine of the character described, the combination of a magazine for holding stereotype plate matrices, means for discharging matrices therefrom, a casting box for receiving the matrices from the mold, and means whereby each used matrix will be pushed from the mold by a matrix entering the mold from the magazine.

16. In a stereotype plate casting machine, the combination with a matrix magazine, of a casting box, and means for discharging a matrix from the magazine in a horizontal plane directly into the casting box, and pushing therefrom in the same plane, a matrix therein.

17. In a stereotype plate casting machine, the combination with a matrix magazine, of a casting box, and means for discharging a matrix from the magazine in a horizontal plane directly into the casting box.

18. The combination in a mechanism for making stereotype printing plates, of a cast-

ing device having means for holding the matrix, with means for ejecting the matrix from the casting chamber after a number of plates have been cast.

5 19. The combination in a mechanism for making stereotype printing plates, of a casting device, and means for ejecting a matrix therefrom.

10 20. The combination in a mechanism for making stereotype printing plates, of a casting device, means for ejecting a cast plate from the casting device, and means for feeding a matrix transversely with respect to the direction in which the plate is ejected.

15 21. In a stereotype plate casting machine, the combination of a casting box, means for ejecting a plate from the casting device in its own plane, and means for feeding a matrix into the casting box in a direction transverse to that in which the plate is ejected and thereafter ejecting the matrix from the casting box.

20 22. In a stereotype plate casting machine, the combination with a magazine for matrices, of a casting box in two sections, and means for moving one of said sections into position to receive a matrix from the magazine and for thereafter moving it into contact with the other section.

25 23. In a stereotype plate casting machine, the combination with a magazine for matrices, of a casting box in two sections, and means for removing one of said sections into position to receive a matrix from the magazine and for thereafter moving it into contact with the other section and for returning it to receiving position, whereby a new matrix can be introduced into the casting box and the old one pushed out.

30 24. In a casting box, the combination of two flat sections movable with respect to each other, a pair of gages fixedly mounted on one section adapted to receive the edges of a matrix, and a pair of gages mounted on the other section at right angles thereto constructed and adapted to form a bevel on the edge of the plate.

35 25. In a casting box, the combination of an upper section having side gages fixed thereto and provided with bevel inner edges with their projecting edges at the bottom, whereby a plate cast in the casting box will be supported by said gages when the bottom section is removed, and a lower section having gages at right-angles to the first named gages fixed thereon and adapted to project over the edges of the matrix, whereby when the lower section is lowered the matrix will be taken with it leaving the plate free to be withdrawn.

40 26. In a casting box, the combination of an upper section and a lower section, said lower section being movable downwardly from the upper section, means on the upper section for supporting the cast plate inde-

pendently of the lower section, and means on the lower section for positively holding the matrix whereby when the lower section is lowered the matrix will be dropped from the plate and kept on the surface of the 70 lower section.

27. In a stereotype printing plate casting box, the combination of an upper mold section, a lower mold section, means for reciprocating the lower mold section toward and from the upper section, and means for adjusting the upper section toward and from the lower section to provide for casting plates of different thicknesses.

28. In a stereotype printing plate casting 80 box, the combination of an upper mold section, means for supporting the same, a lower mold section having means for supporting a matrix, means for reciprocating the lower mold section toward and from the upper section, means for introducing metal therein, and yielding means for pressing each mold section independently toward said metal introducing means.

29. In a stereotype printing plate casting 90 box, the combination of an upper mold section, means for supporting the same, a lower mold section having means for supporting a matrix, means for reciprocating the lower mold section toward and from the upper section, and means for suspending the upper section so as to be free to move slightly, yielding means for moving it into a certain position, and a removable distance piece between the upper and lower sections. 100

30. In a stereotype printing plate casting box, the combination of an upper mold section, means for supporting the same, a lower mold section having means for supporting a matrix, means for reciprocating the lower 105 mold section toward and from the upper section, and a removable distance piece between the upper and lower sections.

31. In a stereotype printing plate casting box, the combination of an upper mold section, means for supporting the same in a fixed position, a lower mold section, means for reciprocating the lower mold section toward and from the upper section, and means on the frame for adjusting the limit of the 115 upper reciprocation of said lower section.

32. In a machine of the character described, the combination of a magazine for holding stereotype plate matrices, means for feeding said matrices out of the magazine in 120 regular order, manually controlled means for feeding the matrices at will, and a casting box for receiving the matrices from the magazine, and means for introducing metal into the casting box when the matrix is in 125 position therein.

33. In a machine of the character described, the combination of a magazine for holding stereotype plate matrices, means for automatically feeding said matrices out of 130

the magazine, means for rendering the feeding means inoperative and a casting box for receiving the matrices from the magazine, and means for introducing metal into the casting box when the matrix is in position therein.

34. In a stereotype plate casting machine, the combination with a magazine for matrices, of a casting box in two sections, and means for moving one of said sections into position to receive a matrix from the magazine and for thereafter moving it into contact with the other section and means for introducing metal into the casting box when closed.

35. In a stereotype plate casting machine, the combination with a magazine for matrices, of a casting box in two sections, and means for moving one of said sections into position to receive a matrix from the magazine and for thereafter moving it into contact with the other section, means for introducing metal into the casting box when closed and for returning the movable section, whereby a new matrix can be inserted and the old one pushed out.

36. In a casting machine, the combination of a casting box adapted to receive a matrix, a pump, and means controlled by the position of the matrix and the casting box for controlling the operation of the pump.

37. In a machine of the character described, the combination of a casting box, a matrix therefor, means for moving a portion of the casting box, a pump for filling the casting box, and means whereby if a complete matrix is in position in the casting box when moved to the limiting position, the pump will be caused to operate to force metal into the casting box.

38. In a machine of the character described, the combination of a casting box, a matrix therefor, means for moving a portion of the casting box, a pump for filling the casting box, means whereby if a complete matrix is in position in the casting box when the movable part is moved to the limiting position, the pump will be caused to operate to force metal into the casting box, but if a portion of the matrix is missing or if the matrix is not in position, the pump will be prevented from forcing metal into the casting box.

39. In a casting machine, the combination of a casting box having a relatively fixed section and a movable section, a matrix, a reciprocable pin in position to be moved by the matrix if said matrix is in position and extends into registration with the pin when the movable section moves into engagement with the fixed section, and means controlled by said pin for introducing metal into the casting box.

40. In a casting machine, the combination of a pump comprising a piston and a valve,

said valve being arranged to prevent the operation of the pump when open, a valve rod, a rock shaft having a latch adapted to engage said rod, a casting box, and means on the casting box adapted to turn the rock shaft and hold the latch in a position to prevent the closing of the valve.

41. In a casting machine, the combination of a pump, a casting box, means for directing metal from the pump to the casting box, and means for automatically and periodically introducing a matrix into the casting box in a direction transverse to that in which the metal is forced into the casting box.

42. The combination with a casting box, of means for introducing metal therein, and means for automatically and positively ejecting a matrix from the casting box in a direction transverse to that at which the metal is introduced into the casting box.

43. The combination of an upper flat casting box section, a lower flat casting box section, said lower section being movable downwardly from the upper section, means mounted on the upper section for supporting the cast plate in stationary position on the bottom thereof independently of the lower section, means on the lower section for positively holding the matrix thereon, whereby the descent of the lower section will directly cause the matrix to be stripped from the plate, and means for engaging the plate when the casting boxes are separated and withdrawing the plate therefrom endwise by motion in its own plane.

44. In a casting machine, the combination of a casting box having an upper fixed member and a lower member movable away from it, means on the upper member for supporting a casting when the lower member has descended, said means extending along two sides of the mold cavity, and means for engaging the lower side of the casting to draw the same from the casting box along said supporting means.

45. In a machine of the class described, the combination of a reciprocating rack, an arm laterally adjustable thereon, a carrier hook mounted on said arm, and a casting box in position for receiving said hook and from which said hook is adapted to withdraw a casting.

46. In a machine of the class described, the combination of a casting box, a reciprocable arm, a hook pivotally mounted on the arm, a spring for pressing said hook up, and means for reciprocating the arm to insert the hook in the casting box and engage a casting, whereby the casting will be withdrawn.

47. The combination of a casting box having means for producing a casting with a notch in the edge thereof, a reciprocatory arm, an adjustable hook on the arm adapted to engage in the notch in the casting, and

means for moving said arm from the casting box to withdraw the casting therefrom.

48. The combination with a casting box, of a reciprocatory member adapted to engage the casting, means for moving said member from the casting box to withdraw the casting therefrom, and means for adjusting the length of stroke of said member.

49. In a stereotype plate finishing machine, the combination with a casting box of means for withdrawing a plate therefrom, means for trimming the edges of the plate as it is withdrawn, and means for thereafter moving the plate in a direction at right-angles 15 to its direction of motion when withdrawn from the casting box.

50. In a stereotype plate finishing machine, the combination with a casting box arranged for casting a plate with its face down, means 20 for withdrawing a plate therefrom in its own plane, and means for trimming the edges of the plate as it is withdrawn and

while in the position in which it was cast in the box.

51. The combination with a casting box 25 in which a plate is cast with its face down, of a finishing mechanism arranged to operate on the plate while in the same position.

52. The combination with a casting box 30 having an upper member for holding a cast plate therein, and a lower member for supporting the matrix, whereby the plate is cast with its face down, and finishing mechanism in position for finishing the plate as it 35 is removed from the casting box while still in the same position.

In testimony whereof I have hereunto set my hand, in the presence of two subscribing witnesses.

HENRY A. WISE WOOD.
